(57) **CLAIM**

The ornamental design for a dispenser with center opening covers, as shown and described.

DESCRIPTION

FIG. 1 is a perspective view of the dispenser with center opening covers showing our new design;

FIG. 2 is a top plan view thereof;

FIG. 3 is a side view thereof, with the opposite side being a mirror image thereof;

FIG. 4 is a bottom plan view thereof;

FIG. 5 is an end view thereof, with the opposite end being a mirror image thereof;

FIG. 6 is a side view thereof with one cover in open condition;

FIG. 7 is a side view thereof with the other cover in open condition; and,

FIG. 8 is a side view thereof with both covers in open condition.

The broken line showing is for illustrative purposes only and forms no part of the claimed design.
